INTERNAL COMBUSTION HAMMER

Carl L. Charles, Winnetka, Ill., assignor to Gas
Tool Patents Corporation, a corporation of
Delaware

Application March 15, 1937, Serial No. 131,052

2 Claims. (Cl. 123—7)

This invention relates to an internal combustion hammer, and more particularly to an improved lower end construction therefor.

One feature of this invention is that it provides improved cushioning means for the impacts in a hammer in raised position; another feature of this invention is that it enables a single cushioning spring to be used; still another feature is that it eliminates clatter, jump, and excessive vibration when the hammer is raised; another feature is that the speed of the hammer is reduced when it is raised from working position; yet another feature is that the desired cushioning is attained without any loss in force of the blows on the tool when the hammer is in working position; other features and advantages of this invention will be apparent from the following specification and the drawings, in which:

Figure 1 is an elevation of a hammer embodying this invention, partly in vertical section; Fig. 2 is a detailed sectional view along the line 2—2 of Fig. 1; Fig. 3 is a vertical elevation of the lower end of the hammer, at right angles to the view in Fig. 1; Fig. 4 is a view of another type of hammer embodying this invention; Fig. 5 is a vertical elevation of the bottom of this hammer, at right angles to the view in Fig. 4; and Fig. 6 is a detailed view of the tool holder along the line 6—6 of Fig. 5. Fig. 7 is a side elevational view of the tool holder of Fig. 5.

The hammer is of the internal combustion type wherein a cylinder 10 has a piston-hammer 11 freely reciprocal therein, the hammer being of the general type shown and described in Mould Patent No. 1,997,072, and other similar patents.

The cylinder 10 and piston 11, with associated mechanism to render them operative, form an internal combustion engine operating on the two-stroke-cycle principle. A charge of air and vaporized gasoline, for example, is supplied from the fuel supply unit 12 to the chamber 13 beneath the piston, where it is partly compressed by the downward stroke thereof. Near the bottom of the working stroke of the piston the charge is transferred from the sub-piston compression space to the combustion space thereabove through the transfer passage 14. The charge is then finally compressed on the upward stroke of the piston, effected by the springs 15 and 16, and is ignited by the spark plug 17 at the proper time, as a result of action of the circuit breaker 18. Combustion of this charge drives the piston downward on its working stroke until the burned gases are discharged through the exhaust port 19 and the cycle is repeated.

Handles 20 and 21 are provided to enable the workman to properly manipulate the hammer, to spot the tool on the working point, and to lift the hammer between operations. Starting is accomplished by manually depressing the starting rod 22 until the piston is near the lower end of its travel, then releasing it so that the piston springs back and compresses a charge above it in the firing chamber. The source of current for ignition is here shown as attached to the spark plug 17 and the circuit breaker 18 by leads 23 and 24 respectively, brought into one handle of the hammer through the cable 25 from an external source.

Referring more particularly to the lower end 15 of the hammer illustrated in Figs. 1, 2 and 3, the cylinder 10 has extending downwardly therefrom an anvil housing 26. This anvil housing is concentric with respect to the cylinder, and therefore with respect to the piston-hammer 11, and 20 is held thereto by tie rods 27 and 28. Beneath the anvil housing and fastened thereto by the same tie rods 27 and 28 is a cap or housing 29. This combination provides housing, coaxial with the piston, for the anvil 30, the anvil sleeve bearing 31, the follower 32, the cushion spring 33, and the split bushing or tool retainer 34.

The anvil comprises a member longitudinally movable in the anvil sleeve bearing 31 and adapted to receive the blow of the piston-hammer 11 30 and transmit it to the tool 35. The anvil 30 is a rather close fit in the sleeve bearing 31, preferably with only a few ten-thousandths of an inch clearance between it and the bearing. It is mushroomed out at the bottom to form a head 36 which abuts a shoulder 37 on the inside of the anvil sleeve bearing 31 to limit the upward movement of the anvil. When the hammer is working the tool 35 is forced upwardly or raised in the hammer by the downward pressure of the weight 40 of the hammer and the operator, so that the tool is at its upper end in contact with the head 36 of the anvil, in turn prevented from further upward movement by the shoulder 37. The sleeve bearing 31 is longitudinally movable in the anvil housing 26, but upward movement is prevented by a shoulder 38.

Immediately beneath the sleeve bearing 31 and abutting it is the follower 32. This follower surrounds the upper portion of the tool 35 and is axially movable in the anvil housing 26. It is supported in a raised position against the sleeve bearing by the cushion spring 33, which has its upper end abutting the bottom of the follower 55

32 and its lower end abutting the split bushing or tool retainer 34.

When the hammer is lifted the tool, as a result of gravity, drops from its working or raised position until the shoulder 39 thereon contacts the bushing 34, whereupon further downward movement of the tool with respect to the hammer body is arrested. The anvil 30 then drops until the head 36 contacts the top surface of the follower 32, and thereafter blows delivered on the anvil by the piston-hammer are absorbed by the anvil, the follower, and the cushion spring 33. It will be noted that when the tool is dropped, the follower 32 has a space of about eleven-sixteenths of an inch through which it can move to absorb the impact delivered by the piston-hammer. The spring 33 is, of course, a relatively heavy coil spring arranged to exert about three hundred and sixty-three pounds upward pressure when the follower 32 is at its lowermost position. The spring is also so arranged that there is some upward pressure, preferably one hundred pounds or less, when the follower 32 is at its upper position illustrated in the drawings. This pressure can be much less, but is preferably about ninety-six pounds.

It will be noted that when the hammer is in working position with the tool extending or raised therein to the position shown in the drawings, the anvil 30 has a distance of only about one sixteenth of an inch through which it can travel before it strikes the upper surface of the follower 32. This is sufficient play for normal working conditions, so that the follower is not called upon to absorb any substantial impacts except when the hammer is lifted, yet return of the anvil does not impart undesirable vibration to the hammer.

It will also be noted that the piston return spring assembly, comprising the piston spring 15 and recoil spring 16, is supported at its lower end by the anvil sleeve bearing 31. This spring combination is under a static compression of from sixty to ninety pounds, preferably about seventy-two pounds, when the piston is down to the point of impact with the anvil. Thus when the piston delivers its blow on the anvil, the piston spring assembly exerts considerable downward pressure on the anvil sleeve bearing which is in turn transmitted to the follower 32. The blow on the anvil by the piston would also be transmitted to the follower except for the upward force exerted by the tool on the anvil, which is a function of hammer weight and the pressure exerted by the operator. When the hammer is lifted and in non-working position, therefore, the follower 32, when driven downward, is returned by the cushion spring 33, but the return is opposed by the force exerted by the piston spring assembly through the anvil sleeve bearing 31, with the inertia of the piston as a reaction against which the spring assembly works. The opposing forces of the piston spring assembly and the cushion spring tend to keep the anvil sleeve bearing 31 and the follower 32 in contact with each other, so that vertical reciprocation is as a unit.

It is believed that when the hammer is lifted from working position and the impact of the blows is being absorbed by the cushion spring, that the sleeve bearing 31 and follower 32 are never in their uppermost position illustrated in the drawing, although sometimes at the bottom of their possible travel, but usually floating there-

between. As soon as the hammer is lifted the tool drops and the anvil drops with it until it contacts the follower 32, thus lengthening the stroke of the piston about one-sixteenth of an inch. Any further drop of the follower 32 in absorbing the blows causes the anvil to drop still lower in the cylinder and thus give a still longer effective stroke. A lower position of the follower 32, since it results in a similar lower position of the anvil sleeve bearing 31 supporting the springs, also may result in less force in the piston spring assembly returning the piston, when the assembly is near most expanded position, thus resulting in a reduced compression of the charge in the firing chamber. The longer time the exhaust port is open, due to the fact that the piston travels further down in the cylinder, also seems to result in a loss of some of the fresh charge. It is believed that these factors so alter the working stroke of the piston as to reduce its power. It is also believed that the arrangement described, with opposed springs above and below, keeps the anvil sleeve bearing 31 and follower 32 in contact with each other and prevents impact therebetween; and that the concentric arrangement of the cushion spring 33 with respect to the cylinder prevents any side components of motion being set up which cause binding or other undesirable action in the impact absorbing unit.

The follower 32 is closely fitted in that part of the housing 26 in which it travels, and the anvil sleeve bearing 31 has the lower surface thereof ground to make a good fit on the ground upper surface of the follower 32. It will be noted, moreover, that when the follower is in the uppermost position shown in the drawings it is in contact not only with the sleeve bearing but with a shoulder on the housing. Thus when the follower and sleeve bearings move downwardly under the influence of impacts of the piston hammer an annular space exists between the upper surface of the follower and the shoulder, with the housing forming the outer wall thereof and the sleeve bearing the inner wall. Inasmuch as some pressure is created within the housing 29 by the downward movement of the follower, and a vacuum created between the follower and shoulder, some air is believed to enter this annular space. The vacuum, moreover, probably draws oil into the space from the surfaces between the sleeve bearing and housing and between the follower and housing. It is believed that when the follower moves upwardly again this mixture of air and oil forms a fluid cushion between the upper surface of the follower and the shoulder of the housing, so that the last minute movement of the follower is cushioned thereon. The follower has been found in practice to contact the shoulder very lightly on its return, since even after long periods of operation of the hammer neither the shoulder nor follower show any signs of wear which would result from heavy impacts at this point.

Whatever the theoretical explanations of the improved results secured may be, practice has proved that the arrangement shown and described is considerably more effective than any other known bottom arrangement for absorbing impact when the hammer is lifted. When the hammer is lifted the speed drops from a working speed of around 1250 strokes per minute to a speed of 1050; the shocks of the impacts of the piston-hammer are absorbed and cushioned by the lower end in such a way that the body structure of the hammer is able to absorb the vibration, without undesired breaking of parts or

fatigue troubles; and the vibration of the hammer when lifted is reduced so that it is relatively smooth running and easily handled and spotted by an operator.

5 In the second or modified form of this invention illustrated herewith in Figs. 4 to 6, a more powerful hammer particularly designed for heavy duty is shown. The particular hammer illustrated weighs about ninety-four and one-half 10 pounds, and delivers about 1550 blows per minute when working. With the exception of differences in bore and the like, the general operation of the engine portion of the hammer is the same as that described in connection with the form shown in 15 Figs. 1 to 3.

The piston-hammer 41 is of larger diameter than that previously described, and weighs about seven and one-half pounds. A piston-hammer much heavier, while it delivers more powerful 20 individual blows, slows down the speed of the hammer so that the total work out-put is not as great; too light a piston, as for example a five pound piston in this two and seven-eighths inch bore, results in high hammer speed but 25 gains less work output. The return springs 42 and 43 are so arranged as to be under a compression of about 82 pounds when the piston is in contact with the top of the anvil 44. The anvil 44 is longitudinally slidable in an anvil sleeve bearing 45, also longitudinally slidable in the recess 46 provided therefor in the anvil housing 47. A follower or tool guide 48 abuts the lower end of the sleeve bearing, being carried by a tool guide housing 49 rigidly, although removably, attached to the lower end of the anvil housing. 30 The tool guide is slidable in its housing, being guided therein by contact at its upper end with the inner wall of the housing and at its lower end with a polygonal opening 50 provided there- 35 through. A cushion spring 51 surrounds the reduced portion of the tool guide, abutting the shoulder 52 on the tool guide at the upper end thereof and the shoulders 53 on the inner side of the housing at the lower end thereof. A poly- 40 gonal opening 54 in the center of the tool guide receives the tool 55 therethrough, the tool being prevented from dropping out of the hammer when it is lifted by engagement of an annular shoulder 56 thereon with a tool holder 57.

50 Referring more particularly to Figs. 5 and 6, it will be seen that the tool holder 57 comprises a yoke member carried at each end thereof by extensions of the tie rods 58 and 59. The holder 57 has a central slot or opening adapted to embrace the tool 55 below the annular shoulder 56. One end of the yoke member, here illustrated on the left side of the hammer, has therethrough an opening adapted to surround and be rotatably journaled on the extension of the tie rod 58. 55 The lowermost part of this extension is provided with a head or annular shoulder 60 and the yoke has a reduced opening embracing the extension thereabove. This mounting enables the yoke member to be readily rotated about the tie rod 60 60 as an axis, but prevents any possibility of its dropping off of the said rod. A spring 61 may be placed between the yoke member and the bottom of the housing 49 to yieldingly urge the yoke member against the head 60 and prevent bounc- 65 ing up and down as a result of the vibration of the running hammer.

The other end of the yoke member, here shown at the right in the figures, terminates in a hooked portion adapted to surround the extended portion 70 of the tie rod 59 on the other side of the

hammer. A ring 62 is slidably carried by this extended portion, and yieldingly pressed downwardly by a spring 63. The ring has a downwardly extending latch portion 64 adapted to retain a portion of the yoke member 57 between it and the extended portion of the tie rod 59.

In order to remove the tool 55, the latch ring 62 is manually raised against the tension of the spring 63 until the latch 64 clears the hooked end of the yoke member, whereupon the yoke is rotated about the extended portion of the tie rod 58 until the central slot is sufficiently removed from the tool that it may be dropped out of the hammer. A new tool may then be inserted in the opening 54 in the member 48, pushed upwardly therein until the shoulder 56 is above the yoke member, and the yoke member then swung back until its hooked end embraces the extension of the tie rod 59 and its central slot embraces the tool. The latch ring 62 may then be permitted to drop until its latch portion holds the hooked end of the yoke in place, whereupon the tool is held in the hammer for any desired operation.

The lower end assembly of the hammer illustrated in Fig. 4 is to scale, and the preferred embodiment of this invention in all respects. The tool guide housing has an outer diameter of 4.5 inches at its largest dimension, and an inner diameter serving as a guide for the upper end of the tool guide 48 of 3.625 inches. The tool guide lying therein has an upper shoulder portion 3.622 inches in diameter and one inch thick from its point of contact with the anvil sleeve bearing 45 to the shoulder 52. The overall length of the tool guide is four and five-eighths inches, and the outer diameter of the reduced portion is 2.25 inches. The material is of steel, heat treated to a Rockwell hardness of from C-50 to C-53. The cushion spring 51 is of seventeen thirty-seconds 40 inch diameter chrome vanadium wire wound right handed in four and three-fourths coils. The metal is treated to a Rockwell hardness ranging from C-42 to C-44. The spring has a three inch mean diameter, and a three and one-quarter 45 inch free length after the ends are closed and ground flat, the wire not being less than five thirty-seconds inch thick at any point after grinding. This spring, in the initial position shown in the drawings has a force of 327 pounds; 50 were the spring to be compressed to closed or solid position it would have a force of about 980 pounds. The play or space between the head of the anvil 44 and the top of the tool guide 48 is three-eighths inch so that when working the 55 tool has that distance within which to move and still absorb all of the work or energy delivered by the piston-hammer. It will be noted that all of the edges of pieces subject to impact strains are chamfered or ground slightly round on the corners. This is necessary in order to avoid fatigue 60 troubles which would otherwise start at the square corners.

It is believed that the reasons discussed in connection with the lower end construction of the 65 first hammer described also explain improved operating results secured here. Whatever the reasons this lower end construction provides a distinctly better hammer under operating conditions than the cushion mechanisms heretofore used. 70 Hammers similar in all respects, except that one had the lower end construction shown in Mould Patent No. 1,997,072 and the other the lower end construction shown in Fig. 4, were tested side by side. Operating on a tamper on gravel both ham- 75

mers ran at 1500 strokes per minute when working. The arrangement illustrated herewith caused the hammer on which it was used to run much more smoothly, the absence of excessive vibration being very apparent. Speed tests made on each hammer when picked up proved that the design illustrated herewith slowed up the hammer to 1100 strokes per minute as against the 1200 strokes per minute of the other hammer, 10 with a much more comfortable and easier handling hammer for the operator. The older type hammer produced quite a clatter and frequent jumps when held up, noticeably absent in the hammer constructed as illustrated herewith.

15 Improved means for locking the spark plug 65 in place is also illustrated herewith. The spark plug has an annular shoulder or ring 66 thereon beneath which a sealing gasket 67 is placed when the spark plug is drawn up against the shoulder 20 of the wall of the hammer. Immediately adjacent one side of the spark plug is the bolt 68 and lock nut 69 holding in place a substantially L-shaped bracket member 70 having the extended end thereof pressing against the top of the annular ring 66. It will be noted that this bracket is 25 so constructed and shaped as to be out of contact with the body of the hammer except at one point on the side of the bolt furthest from the spark plug. Drawing up the bolt 68 thus throws 30 considerable locking pressure on the ring 66, preventing the spark plug from vibrating or loosening from its proper position on the body of the hammer.

35 Considerable trouble has been experienced in keeping a spark plug in place in an internal combustion hammer of the type shown and described here, since the terrific vibration causes the plug to work loose even though it is ordinarily tightened to refusal with a wrench. Various methods 40 of locking the plug in place have heretofore been tried, but in each case that required the setting of the plug at a particular position in order that a piece might engage the hexagonal portion, for example. The present invention enables the plug 45 to be drawn up to refusal in the usual manner, and then the additional locking means applied to insure against its vibrating loose.

The fact that the bracket or locking member 50 70 bridges the space on the cylinder wall, rather than contacting it throughout its length, insures a firm frictional locking grip on the spark plug shoulder 66. That is, the bracket contacts the wall of the cylinder at one end and the shoulder of the spark plug at the other end, with the bolt 55 68 lying therebetween. Drawing up on the bolt

thus puts pressure on only two points, and insures the full desired pressure being applied to the shoulder of the spark plug to frictionally lock it in place.

5 While I have shown and described certain embodiments of my invention, it is to be understood that it is capable of many modifications. Changes, therefore, in the construction and arrangement may be made without departing from the spirit and scope of the invention as disclosed 10 in the appended claims.

I claim:

1. An internal combustion hammer of the character described, including: a cylinder; a piston-hammer freely reciprocal therein; a tool 15 longitudinally movable in said hammer; an anvil sleeve bearing longitudinally movable in said cylinder; an anvil slidably mounted therein for transmitting the blows of said hammer to said tool when in raised position; a follower for receiving the blows of said hammer when said tool is in lowered position, said follower being in contact with said sleeve bearing but spaced from said anvil when said tool is in raised position; a coil 20 spring between said sleeve bearing and said piston and supported by said sleeve bearing; and a cushion spring exerting an upward force on said follower and sleeve bearing, said spring being coaxial with respect thereto and stiffer than said first mentioned spring; said follower comprising 25 an enlarged portion and a reduced portion lying within said cushion spring, said follower being guided at each end thereof.

2. An internal combustion hammer of the character described, including: a cylinder; a piston-hammer freely reciprocal therein; a polygonal tool longitudinally movable in said hammer; an anvil for transmitting the blows of said hammer to said tool; a follower longitudinally movable for receiving the blows of said hammer when 40 said tool is in lowered position, said follower comprising a portion of enlarged diameter and an elongated portion of reduced diameter having a polygonal lower end, the follower having a polygonal opening therethrough adapted to receive 45 said tool; a housing rigidly mounted beneath said cylinder and having a polygonal portion forming a guide for said lower end, whereby the tool projecting through said follower is prevented from turning with respect to said hammer; a 50 spring between said anvil and said piston; and a cushion spring within said housing exerting an upward force on said follower.

CARL L. CHARLES. 55
